LADISLAS W. SCHWENK, OF FLUSHING, NEW YORK.

STAND AND TILTER FOR BARRELS AND THE LIKE.

Application filed November 17, 1925. Serial No. 69,662.

My invention consists of a combination stand and tilter for heavy barrels, hogsheads, iron drums and the like, and comprises simple, effective and convenient means 5 for picking up the barrel and preventing it from sliding off the stand, for preventing the stand from slipping on the floor or ground, for holding the stand and barrel fixed in horizontal position and for tilting 10 it when desired to draw off the contents or removing the barrel from the stand.

In order that the nature of my invention may be clearly understood I shall first describe in detail the mode in which I at present 15 prefer to carry the invention into practice and then point out the various features of the invention in the claim.

Reference is to be had to the accompanying drawings forming part of this specification in which the same parts are designated 20 by like letters in all the figures.

Figure 1 is a side elevation of a barrel stand and tilter embodying my invention.

Figure 2 is an end elevation of the same. 25 Figure 3 shows the stand tilted to pick up the barrel.

As shown in the drawings I prefer to make the body of the stand of two parallel semi-circular rockers 5 and 6, of channel or 30 other rigid sections of iron, each formed at the bottom with sharp teeth 7 to bite the floor or ground and prevent the stand from slipping.

Each rocker 5 and 6 has its arms connected by a rigid longitudinal bar 9, and above said bar 9, each end of each rocker arm is bent outward transversely to a circular segment 10 and said outwardly bent segments of the two rocker arms are riveted at each 35 end of the stand to a transverse circular

segmental bar 11, curved in the vertical plane.

The two end segmental bars 11, form fitting rests for the respective ends of the barrel. 45

On one segmental rest bar 11 are fixed two or more catches 12 projecting endwise outward so as to hook over the end of the barrel and keep it on the rests.

On the arms at each end of the rockers 5 and 6 is pivoted to swing longitudinally outward a pair of legs 13 rigidly connected by cross bars 14, which legs can be lowered to the ground as shown in Figure 1 to hold the stand and barrel fixed in a horizontal position or can be swung longitudinally outward out of the way to tilt the stand and barrel fully for removing the latter as shown in Figure 3 or only partially for drawing off its contents. 50 55 60

The tilting stand thus formed can be easily and cheaply manufactured and is very strong and serviceable.

It is evident that many changes may be made in the specific construction and arrangement described without departing from the boundaries of my invention as defined by the following claim. 65

I claim as my invention:—

A stand and tilter for barrels and the like 70 consisting of longitudinal rockers having their upper arms each bent outward transversely to form a segment of a circle for supporting the barrel, and circular transverse rest segments corresponding and secured to 75 said segmental arms of the rockers to be stiffened and supported thereby and rigidly connecting the rockers.

In testimony whereof I affix my signature.

LADISLAS W. SCHWENK.
